UNITED STATES PATENT OFFICE.

RAYMOND E. CRANE, OF WILMETTE, ILLINOIS.

DESIGN FOR A WASHBASIN.

57,770.

Specification for Design.

Patented May 3, 1921.

Application filed August 26, 1920. Serial No. 406,235. Term of patent 14 years.

To all whom it may concern:

Be it known that I, RAYMOND E. CRANE, a citizen of the United States, residing at Wilmette, in the county of Cook and State of Illinois, have invented a new, original, and ornamental Design for a Washbasin, of which the following is a specification, reference being had to the accompanying drawing, forming part thereof.

The figure is a plan view of a washbasin, showing my new design.

I claim:

The ornamental design for a washbasin as shown.

In testimony whereof I affix my signature in presence of two witnesses.

RAYMOND E. CRANE.
